UNITED STATES PATENT OFFICE

148,260

DESIGN FOR A FLAG HOLDER OR SIMILAR ARTICLE

Iver Syverstad, Winthrop, Mass.

Application April 11, 1947, Serial No. 138,303

Term of patent 14 years

(Cl. D29—17)

To all whom it may concern:

Be it known that I, Iver Syverstad, a citizen of the United States, residing at Winthrop, in the county of Suffolk, in the Commonwealth of Massachusetts, have invented a new, original, and ornamental Design for a Flag Holder or Similar Article, of which the following is a specification, reference being had to the accompanying drawing, forming a part thereof, in which:

Figure 1 is a top plan view of a flag holder showing my new design, Figure 2 is a front elevational view thereof, and Figure 3 is a perspective view thereof.

I claim:

The ornamental design for a flag holder or similar article, substantially as shown.

IVER SYVERSTAD.
